HINGE BRACKET FOR FIXTURES

Roy S. Sanford, Oakville, Conn., assignor to
The Autoyre Company, Incorporated, Oakville,
Conn., a corporation of Connecticut

Application March 16, 1940, Serial No. 1324,268

6 Claims. (Cl. 248—205)

This invention relates to a hinge bracket for fixtures and has special reference to a bracket for attachment on a wall or other support in which the securing means for the bracket may be concealed from view and the fixture may be swung outwardly from the support.

More particularly, this invention relates to a bracket comprising a supporting plate adapted to be secured to a wall or other support and a cover plate hinged to the supporting plate for enclosing the securing means therefor and for carrying a fixture.

Brackets are ordinarily secured to a wall or other support by screws or the like in which the heads thereof are exposed to view. It is desirable to conceal such securing means from view in order that the appearance in design of the bracket may be pleasing. Applicant is aware that constructions in which the securing means are concealed from view are not in themselves new. Constructions of this type of which applicant is aware, however, have the disadvantage that the portion thereof adapted to be secured to the wall is entirely separated from that portion on which the fixture is mounted. When the fixture is to be mounted on the wall, the supporting portion of the bracket is first affixed to the wall after which the fixture and its associated element for attachment to the supporting portion is disposed in place.

In many, if not most, instances the supporting portion of the bracket which is affixed to the wall is not properly placed so that the fixture will not be supported in a symmetrical position. It is the purpose of the present application, therefore, to hingeably support the fixture on the bracket so that it may be swung out of the way to fasten the securing means and is readily available when positioning the supporting portion thereof on the wall to determine the final position with an initial placement thereof on the wall. In other words, the fixture forming a part of the bracket by being hingeably secured thereto is always available for purposes of alignment of the supporting portion thereof as the construction is being secured to the wall.

In many instances it is desirable to swing the fixture out from the wall for access to articles supported thereby after the supporting portion thereof is fixed to the wall, in a manner that is convenient and expedient. For example, a towel bar is illustrated in the drawing in which the ends thereof are curved in a direction toward the wall to rest in a position closely adjacent thereto when supporting a towel, washcloth, or the like.

It is inconvenient to thread the towel, washcloth, or the like, through the space between the bar and the wall and in order to conveniently hang these members on the bracket the hinged fixture may be swung outwardly from the wall to afford a very substantial clearance, the fixture being swung toward the wall to a latched position after use.

In attracting prospective customers for the purchase of a construction in the retail stores, it is desirable to provide a display card and holder, the display card ordinarily illustrating conditions of use, features of construction, and method of assembly of the construction to a support. Fixtures of the type illustrated in the drawing, when offered for purchase in retail stores, are ordinarily contained in bins and in this mass relation are not sufficiently colorful for purposes of attracting prospective purchasers. Thus a card on which the fixture may be mounted may be given various bright colors to set off the otherwise colorless devices and acts to separate each individual device from the mass. The provision of a hinged bracket affords the opportunity to readily assemble a card for purposes of instruction and display thereto and permits and invites an examination thereof by the prospective purchaser conveniently. Further, a hinged construction of the type disclosed herein permits the disposal for storage of the screws or other securing means between the hinged members so that such securing means are readily available and are not subject to loss.

One of the objects of this invention is to provide a bracket for a fixture or the like, as above indicated, in which the fixture is connected to the supporting portion thereof during the time that the supporting portion thereof is fixed to the wall in order to obtain a symmetrical disposition of the fixture with respect to the wall and in which the securing means thereof may be concealed from view.

Another object of this invention is to provide a bracket for a fixture or the like of the hereinabove mentioned type, which will be convenient for examination by a prospective purchaser, which will facilitate the assembly of the display card thereto for purposes of attracting the attention of the prospective purchaser, and which will enclose the securing means necessary for the installation thereof.

It is also an object of this invention to provide a bracket for holding a fixture or the like of the type above noted wherein the fixture may

be swung outwardly from the wall to a position readily accessible for convenient use.

Other objects and advantages of this invention will hereinafter be more particularly pointed out and, for a more complete understanding of the characteristic features of this invention, reference may now be had to the following description when taken together with the accompanying drawing, in which latter:

Figure 1 is a perspective view of a hinge bracket for carrying a fixture, the bracket embodying the features of this invention and the hinge being shown at an upper edge thereof:

Fig. 2 is a perspective view of the construction shown in Fig. 1 with the fixture and one of the hinged elements swung outwardly from a supporting wall to which the other element of the hinge bracket construction is secured;

Fig. 3 is an enlarged central vertical sectional view taken on the line 3—3 of Fig. 1, showing the fixture fragmentarily;

Fig. 4 is an enlarged bottom view of the hinged cover portion of the bracket showing fragmentarily a portion of the fixture secured thereto;

Fig. 5 is a perspective view similar to Fig. 1 showing a different form of fixture and showing the hinge of the bracket disposed at a lower edge thereof;

Fig. 6 is a perspective view of the construction of Fig. 5 showing the fixture and cover plate of the bracket swung outwardly from the wall;

Fig. 7 is an enlarged central vertical sectional view taken on the line 7—7 of Fig. 5 showing a fragmentary portion of the fixture;

Fig. 8 is a rear elevational view of a fragmentary portion of a bracket embodying the features of this invention in which is incorporated a different type of latching means for holding the hinged members in detachable engagement; and

Fig. 9 is a perspective view showing a still further form of fixture embodying the features of this invention.

Referring now to the drawing and more particularly to Figs. 1 to 4, inclusive, thereof, the construction embodying the features of this invention is shown as comprising a supporting plate 10 adapted to be secured to a wall or other support and a cover plate 11 hinged to the supporting plate 10. Both the supporting and cover plates are preferably formed of sheet metal, the specific embodiment shown comprising thin sheet steel which is plated with nickel or chromium.

The supporting plate 10 is provided with spaced apertures 12 and 13 for receiving screws 14 and 15, respectively, or other securing means. The aperture 12 communicates with a slit 16 extending upwardly therefrom through a rolled edge 17, the latter forming a split bearing for receiving a pin 18. The aperture 13 communicates with a slit 19 extending longitudinally through the edge of the supporting plate and also communicates with a laterally extending slit 20 terminating within the confines of the supporting plate 10.

The cover plate 11 is preferably embossed to provide a compartment 21 between it and the supporting plate or, in other words, the front face of the cover plate is provided with a peripheral flange 22 extending angularly therefrom in the direction of the supporting plate. The peripheral flange 22 is preferably of a size and shape substantially the same as the peripheral edge of the supporting plate 10 for fitting thereover so that the supporting plate is wholly concealed. The compartment 21 houses the securing means such as the screws 14 and 15 when the

construction is offered for sale at retail stores and conceals the securing means after the bracket and fixture are mounted on a supporting wall. The compartment may also be employed for the purpose of receiving a portion of a display card in order that the construction might be held thereto for display on the counter.

Spaced ears 23 are extended from the flange 22 on one side of the cover plate, the ears being rolled into bearings for receiving the pin 18 to form the hinge connection between the cover plate and the supporting plate. The flange 22 on an edge opposite to that of the hinge is provided with spaced cutaway portions 24 providing therebetween a substantial rigid projection 25. Ears 26 are spaced on opposite sides of the slit 19 and extend from the edge of the supporting plate opposite to that of the hinged edge thereof, the ears being received in the cutaway portions 24. The ears are preferably of a substantially elliptical shape so that upon entering the cutaway portions 24 engagement is had with the projection 25 to force the ears apart and effect a snap engagement therewith, the slit 19 permitting a resiliency of the ears to effect such engagement.

A fixture 27 in the form of a combination tumbler and toothbrush holder is welded or otherwise secured to the front face of the cover plate 11. Such a fixture is shown for purposes of illustration only and it is to be understood that various types of fixtures of the like may be secured to a wall or other support by the bracket of this invention. When it is desired to secure the fixture to a wall or other support, the fixture is always in position such that a symmetrical alignment thereof may be had during the actual attaching of the securing means on the wall. When the fixture is thus attached the cover plate is dropped and latched in position ready for use.

Referring now more particularly to Figs. 5 to 7, inclusive, of the drawing, a bracket embodying the features of this invention is shown as comprising a supporting plate 28 adapted to be secured to a wall or other support and a cover plate 29 hinged to the supporting plate. The structures of the supporting plate and the cover plate are identical with that above described with reference to Figs. 1 to 4, inclusive, and it is not believed to be necessary to repeat such description.

It is sufficient to state that a fixture 30 in the form of a towel bar is attached to the cover plate to show a modified form of fixture construction and that the hinge between the cover plate is disposed oppositely to that of the above described embodiment. In other words, the latching means are disposed at the top of the bracket instead of at the bottom as in the previously described embodiments and the hinge is disposed in the bottom in the present figures instead of at the top as in the previously described embodiments.

The same features are obtained in the present described embodiment as in the previously described construction, the compartment formed by the cover plate, in which the body portion has a peripheral flange of a size and shape substantially the same as the peripheral edge of the supporting plate, housing the securing means when on display on a counter and also securing the fixture and bracket to a display card for the attraction of prospective purchasers. When mounted on the wall, the securing means are concealed from view and in this manner do not detract from the appearance of the design.

As shown more particularly in Fig. 6 when the

cover plate is swung outwardly from the wall the towel bar is likewise carried therewith in order to obtain a substantial clearance between the wall and the towel bar in order that towels, washcloths, or the like, may be readily and conveniently disposed thereon. When the cover plate is swung backwardly to a latched position adjacent the wall, the towels thereon are firmly secured in position for hanging.

Referring now more particularly to Fig. 8 of the drawing, a modified form of bracket construction is shown wherein the supporting member 31 is provided with space gears 32 and 33 between which resilient ears 34 may be frictionally engaged, the ears 34 extending from the cover plate 35. In this embodiment the details of construction of the remainder of the bracket are the same as in the previously described embodiments with the exception that the latching means thereof have been modified as set forth above.

It is considerably more difficult to align a plurality of brackets to receive a towel bar or the like, should the brackets be separated from the bar, and in the form of construction shown in Fig. 9, not only are the features previously recited with respect to the other embodiments present, but the hinged brackets afford an opportunity for correct alignment during installation.

While several embodiments of this invention are herein shown and described, it is to be understood that various modifications thereof may be apparent to those skilled in the art without departing from the spirit and scope of this invention and, therefore, the same is only to be limited by the scope of the prior art and the appended claims.

I claim:

1. A bracket comprising a supporting plate adapted to be secured to a wall or other support, and a cover plate hinged to said supporting plate for carrying a fixture and embossed to provide a hollow space between said plates for enclosing the securing means for said bracket.

2. A bracket comprising a supporting plate adapted to be secured to a wall or other support, an embossed cover plate hinged adjacent one edge thereof to said supporting plate for enclosing the securing means therefor and for carrying a fixture, at least one of said plates being of resilient material, and co-operating latching members formed integrally with and adjacent edges of said plates opposed to the hinged edges for detachably securing said cover plate against movement relative to said supporting plate.

3. A bracket comprising a sheet metal supporting plate adapted to be secured to a wall or other support, an embossed cover plate hinged

adjacent one edge thereof to said supporting plate for enclosing the securing means therefor and for carrying a fixture, spaced resilient ears on an opposed edge of one of said plates, and a rigid projection on the other of said plates for detachable engagement between said ears for securing said cover plate against movement relative to said supporting plate.

4. A bracket comprising a supporting plate having apertures therein adapted to receive securing means for mounting said supporting plate on a wall or other support, an embossed cover plate for enclosing said securing means and for carrying a fixture, a hinge on adjacent edges of each of said supporting and cover plates for permitting a relative swinging movement therebetween, spaced resilient ears on said supporting plate extending angularly therefrom in the direction of said cover plate, and a rigid projection on said cover plate extending angularly therefrom in the direction of said supporting plate for frictional engagement between said spaced resilient ears for detachably securing said plates against relative movement therebetween.

5. A bracket comprising a supporting plate having apertures therein adapted to receive securing means for mounting said supporting plate on a wall or other support, one of said apertures communicating with a transverse slit, an embossed cover plate for enclosing said securing means and for carrying a fixture, a hinge on adjacent edges of each of said supporting and cover plates for permitting a relative swinging movement therebetween, spaced ears on an opposed edge of said supporting plate, said ears being on opposite sides of a slit in said supporting plate extending for communication with said transverse slit, and a projection on said cover plate extending therefrom between said spaced ears for frictional engagement therewith to detachably secure said plates against relative movement therebetween.

6. Bracket means for supporting a fixture, comprising a supporting plate having means for securement to a support, means fixedly related to said fixture shaped to conceal at least the portion of said plate containing said securement means, means for hinging said fixedly related means and said fixture on said supporting plate for movement from a position wherein said securement means are exposed to a position wherein said securement means and said plate portion are concealed, and means for latching said fixedly related means and said fixture in the latter of said positions.

ROY S. SANFORD.
